UNITED STATES PATENT OFFICE

GEORGE W. FARRELL, OF AU SABLE FORKS, NEW YORK, ASSIGNOR TO
ADELLE FARRELL, OF SAME PLACE, AND ALBERT W. SHIELDS AND
B. B. MASON, OF KEESEVILLE, NEW YORK.

VEHICLE-GEAR.

SPECIFICATION forming part of Letters Patent No. 641,945, dated January 23, 1900.

Application filed March 31, 1899. Serial No. 711,260. (No model.)

To all whom it may concern:

Be it known that I, GEORGE W. FARRELL, a citizen of the United States, residing at Au Sable Forks, county of Essex, and State of New York, have invented certain new and useful Improvements in Vehicle-Gears, of which the following is a specification.

The invention relates to such improvements; and it consists of the novel construction and combination of parts hereinafter described and subsequently claimed.

Reference may be had to the accompanying drawings, and the numerals of reference marked thereon, which form a part of this specification.

Similar numerals refer to similar parts in the several figures therein.

Figure 1 of the drawings is a top plan view of my improved gear. Fig. 2 is a view in side elevation of the same. Fig. 3 is a central vertical cross-section of the same, taken on the broken line 3 3 in Fig. 2, showing the pivotal connection by which the springs are connected with each other. Fig. 4 is a side view of one end of the cross-bar detached.

The hind axle 1 and the bolster or head-block 2 are of the usual form, and the latter may be secured to the front axle (not shown) in any known manner.

30 The longitudinal steel springs 3 3 are each secured at one end to the head-block and at the other end to the hind axle, as by the shackles 4 4 4 4, which are bolted upon and inclose the axle and head-block, respectively, in the usual manner. The shackles are provided with projecting ears, between which the ends of the steel springs are respectively secured by bolts in the usual manner, as shown at 5 5 5 5.

40 The longitudinal spring-boards 6 6 are rigidly secured at their ends to the head-block and axle, respectively, in a known manner, as by bolts 7 7, passing down through the boards and the head-block or axle. As shown in

45 Fig. 2, the ends of the boards rest on top of the block and axle, while the ends of the metallic springs are supported in a lower plane in the shackles.

The metallic springs are normally arched, 50 so that the middle part of each is several

inches higher than the ends. The normal form of the spring-boards is approximately straight. The middle parts of the metal springs and boards are forced to occupy approximately the same level by means of the 55 cross-bar 8, the ends of which are provided with a shoulder 9 and threaded stem 10, adapted to enter an eye formed in the lug 11, depending from the middle part of the metallic spring adjacent thereto. Each end of 60 the cross-rod is thus secured to one of the metallic springs by nuts 12, applied to the threaded projecting ends of the stems 10, the stems being left free to turn in the respective lugs. The middle part of each spring-board 65 being superposed upon the cross-rod is firmly secured thereto in a known manner, as by bolts 13.

The spring-blocks 14 14 are secured to the respective metal springs, as by means of clips 70 15 15, which respectively embrace a spring-block and a metal spring and are provided with screw-threaded stems projected downwardly through the metal plate 16, integral with the lug 11, and secured by nuts 17 on the 75 projecting ends of said stems, whereby a spring-block, a metallic spring, and a lug 11 are all held firmly together, as shown.

By having the metallic springs normally arched and the spring-boards forcibly arched 80 one set of springs acts against the other set when there is no load or strain. Such action tends to prevent excessive reactionary upward movement of the parts in passing over unusual obstructions in use. An excessive downward movement is prevented by 85 the sustaining aid of the spring-boards when their middle parts are bent down below their ends.

A vehicle provided with my improved 90 springs will be nearly as responsive to a light as to a heavy load, thus enabling either two or four persons to ride in the same wagon with approximately the same degree of comfort.

By having two sets of springs pivotally connected with each other at their middle parts without any rigid connection between the spring-boards and the spring-blocks there is little or no vibration or jerky movement communicated to the spring-blocks and wagon- 95 100

body by the vibratory movement of the stiff ends of the spring-boards as they are vibrated by the vertical movement of the wheels and axles in passing over rough roads.

5 The wagon-body (not shown) may be secured to the spring-blocks in any known manner.

What I claim as new, and desire to secure by Letters Patent, is—

- 10 1. In a vehicle-gear, the combination with the head-block and hind axle, of normally-arched metallic springs fixedly connected with both the block and axle; a normally-straight spring-board fixedly connected with both the block and axle; and means for securing the middle parts of the springs and board approximately in a common horizontal plane, substantially as described.
- 15

2. In a vehicle-gear, the combination with the head-block and hind axle, of metallic 20 springs with relatively-flexible ends connecting the block and axle; a spring-board with relatively-inflexible ends connecting the block and axle; a spring-block rigidly secured to the middle part of the springs; and a pivotal 25 connection between the board and springs, whereby the vibratory movements of the board ends do not communicate similar movements to a spring-block, substantially as described.

In testimony whereof I have hereunto set my hand this 30th day of May, 1898.

GEORGE W. FARRELL.
